(57) **CLAIM**

The ornamental design for a cluster box indicator, as shown and described.

DESCRIPTION

FIG. 1 is a front elevational view of a cluster box indicator showing our new design, the rear, right, and left side elevational views being identical.

FIG. 2 is a top plan view.

FIG. 3 is a bottom plan view; and,

FIG. 4 is a perspective view thereof showing the bottom, front, and right sides.

1 Claim, 4 Drawing Sheets

FIG. 1

FIG. 2

FIG. 3

FIG. 4
